UNITED STATES PATENT OFFICE.

JAMES THORNTON, OF ST. JOSEPH, MISSOURI.

STRAP-WORKING MACHINE.

969,308.

Specification of Letters Patent. Patented Sept. 6, 1910.

Application filed June 9, 1909. Serial No. 501,188.

To all whom it may concern:

Be it known that I, JAMES THORNTON, a citizen of the United States, residing at St. Joseph, in the county of Buchanan and 5 State of Missouri, have invented certain new and useful Improvements in Strap-Working Machines, of which the following is a specification, reference being had therein to the accompanying drawing.

10 My invention relates to improvements in strap working machines, and particularly applies to that class of machines, which are used for working straps of leather, in the manufacture of harness and the like; and the objects of my improvements are to provide a 15 neat, simple, substantial and durable strap working machine, which will automatically feed leather straps, in rapid succession one at a time into said machine, punch vari- 20 ously spaced holes of any predetermined diameter, through said straps skive one of the ends thereof, die cut, to any desired shape, certain parts of said straps and billet or round the other ends, and thereafter au- 25 tomatically eject said straps from the machine, into a rack; and be readily adjusted to proper adjustment for performing any one or all of the useful operations, on straps of various lengths, widths and thicknesses. 30 Further objects are, to so construct said machine, that it shall be positive in its movements, and accurate in the performance of the described operations, occupy the minimum amount of floor space, be comparatively cheap in cost of manufacture, and require the minimum amount of power.

I attain these objects by the mechanism illustrated in the accompanying drawing, in which;—

40 Figure 1. is an end view. Fig. 2. is a longitudinal section, on the line X X, seen in Fig. 1., looking toward the left. Fig. 3. is a transverse section, on the line Y Y, seen in Fig. 2 looking toward the right. Fig. 4. is a longitudinal section, on the line Z Z seen in Fig. 1., looking toward the right, showing the parts in punching position. Fig. 5. is a section, similar to Fig. 3., showing the parts in feeding and ejecting position. Fig. 45 6 is a horizontal section, on the line U U, seen in Fig. 1., looking downward. Fig. 7. is an enlarged view, in perspective, of a strap support and a portion of the table of the machine. Fig. 8. is an enlarged view in 50 perspective of one of the other various forms of strap supports that are used. Fig. 9 is

an enlarged front view in detail, of the skiver. Fig. 10 is an enlarged transverse section of the die holder, on the line V V, seen in Fig. 4 looking toward the right. 60 Fig. 11 is an enlarged section in detail of certain parts, cut transversely to the driving bars, on the line W W, seen in Fig. 3, looking toward the left. Fig. 12 is an enlarged longitudinal section, in detail of a part of 65 one of the ejectors, on the line T T, seen in Fig. 11. Fig. 13 is an enlarged top plan in detail of the strap stop and of a part of the feed plate. Fig. 14 is a top plan of the strap box extension and part of the strap 70 box.

My invention comprises an adjustable strap box, a strap feeding mechanism, a strap punching and die cutting mechanism, a skiving mechanism, an ejecting mechanism 75 and suitable supports for said mechanisms; all of which are hereinafter described.

Legs 1, secured together by the three tie rods 2, support two yokes, 3 and 3', secured thereon by bolts 3''; said yokes are secured 80 together by tie rods 4 and 5 and tie bar 6. Said tie bar is L shaped and has slots 6' through the front portion thereof, through which pass screws 7, screwed into throat plate 8, for adjustably securing said plate to 85 said tie bar. Strap box 9 is secured at each of the two ends thereof, to blocks 10, provided with slots 10', through which pass, cap screws 10'', screwed into table 11, for securing said strap box in slidably adjust- 90 ment on said table. Strap box 9 is provided with extension 12, slidably secured thereto, by having the turned edges of said extension, slidably in the return bent edges 9' of said strap box. Said extension is provided with 95 strap gage 13, adjusted to various lengths of straps 14, by passing pin 15, downward through an aperture in strap box 9 and through the desired one of apertures 12' formed through the upper turned edge of ex- 100 tension 12, seen in Fig. 14.

The space or throat between throat plate 8 and table 11 is secondarily adjustable by raising and lowering said plate, adjustably secured to said tie bar 6, as described, 105 and is primarily adjusted by raising and lowering table 11, secured on brackets 16, provided with slots 16', through which loosely pass the cap screws 16'', the heads of which, slidably retain said brackets in 110 place, supported on adjusting screws 17, screwed through projections 18, formed on

the lower corners of yokes 3 and 3'. Screws 17 are provided with hand wheels 19, having notches 19' formed in their peripheries, engaged by springs 20, secured to the two front legs 1.

Carrier bars 21, slideable in channels 21', in table 11, are secured to drive plate 22, (see Figs. 1 and 11,) by screws 22' and 22'', the latter of which also secure drive arm 10 23, (having slot 23' formed therethrough,) to the center of said drive plate.

Drive plate 22 is provided with upward extensions 22', (see Fig. 11,) which extend upward through slots 24, formed through 15 table 11, from the bottoms of channels 21'. Said carrier bars 21 are reciprocatively moved in said channels, as hereinafter described, and carry thereon, four ejector bars 25 and the centrally situated push bar 26, 20 and said bars carry thereon, the feed plate 27, provided with slots 27', see Fig. 6. Through slots 27' and apertures in said push bar and ejector bars, pass the thumb screws 28, screwed into carrier bars 21, for 25 providing securing means, whereby said bars are secured together and adjustable securing means, whereby said feed plate is adjustably secured on said bars.

Loosely projecting through slot 23' in 30 drive arm 23 is the drive stud 29, secured in the upper end of drive rod 30, which carries friction rolls 31, intermittently driven by cam 32, secured on drive shaft 33, rotatably mounted in yokes 3 and 3' and having drive 35 pulley 33' secured on the outer end thereof, adapted to be driven by a belt, not shown.

Drive rod 30 is slidably mounted on shaft 33 and tie rod 4, (see Figs. 3 and 5,) which pass through slots 30' and 30'', respectively, 40 formed in said drive rod, retained in position, on shaft 33 between cam 32 and collar 34, secured on said shaft. It will be seen that cam 32 is of such form, that in one revolution of shaft 33, from the 45 position seen in Figs. 1 and 3, said cam intermittently moves feed plate 27, in the following manner. During the first fourth of said revolution, said feed plate is held in the position seen; during the second fourth, said 50 plate is moved from said position, to the position seen in Fig. 5 thereby pushing or feeding the bottom strap 14' of straps 14, to the position seen at 14'', in Fig. 5, from the position seen in Fig. 3; and there holds said 55 feed plate, during the third fourth of said revolution. During the last fourth, said plate is moved from the position seen in Fig. 5, back to the point seen in Fig. 3, thereby providing intermittent reciprocating means, 60 whereby feed plate 27 is intermittently reciprocated in channels 21' in table 11.

Referring to Fig. 7, strap supports 35, provided with slots 36 are adjustably secured to table 11, by screws 37, passed 65 through said slots and screwed into threaded

apertures 38, in said table. Said supports have cut-outs or apertures 39, therethrough of various sizes and shapes to conform with cutting dies 40, which are cutting punches and cutting dies of various sizes and shapes, 70 such as are well known to the strap workers art. One of the other various forms of said strap supports is seen in Fig. 8, which form is one, adapted to support a strap, while die cutting the same.

Dies 40, see Fig. 6, are used singly or in groups, as the nature of the work may require; and since said dies, except as to size and shape, are exactly alike in their construction and operation, a detailed description of one is sufficient. Die 40 is rigidly secured in die base 41, the lower portion of which is detachably secured at any desired point in channel 42', of die carrier 42, by screws 43. Referring to Figs. 4 and 10, said die carrier is provided with two legs 44; and since said legs are exactly alike in their construction and operation, a detailed description of one is sufficient.

The ends of die carrier 42 are guided in 90 slots 42'' formed in yokes 3 and 3', while the leg 44 thereof is guided by shaft 33, which passes through slot 44' formed in said leg, which is supported by its rotatably secured friction roll 45, riding on cam 46, secured on shaft 33. Said leg carries friction roll 47, contacting the lower surface of said cam; thereby providing intermittent moving means, whereby said die carrier and the dies 40, are intermittently moved upward and 100 downward. It will be seen that cam 46 is of such form and is secured on shaft 33, in such time with the movements of cam 32 and feed plate 27, as hereinbefore described, that during said first fourth of the described 105 revolution of shaft 33, die 40 is moved downward from the position seen in Fig. 1, to the position seen in Fig. 5, and there held by cam 46 during the second fourth; then from this position, through the third fourth, said 110 die is moved upward to the position seen in Figs. 1 and 3, through strap 14'' and against die block 48, thereby die cutting said strap. Die block 48 may be of any suitable material, such as Babbitt metal, wood, etc., and 115 is detachably secured by screws 48', in die block holder 48'', secured to tie bar 6 by screws 48''. During the last fourth of said revolution of shaft 33, die 40 is held in the position seen in Fig. 3, and acts as holding 120 means, whereby strap 14'', is held, during the hereinafter described skiving operation.

It will be seen and understood that ejector bars 25, provided with spring ejectors 25', (see Fig. 12,) depressible into mortises 25'', 125 formed in said bars, and push bar 26, (see Fig. 5,) travel with feed plate 27, in its previously described movements. In the movement of ejector bars toward the left, the die cut straps 14'', are pushed or ejected 130

to the position seen at 14^a in Fig. 5, by spring 5
ejectors 25', carried on bars 25, from whence 5
said strap gravitates to the position seen at 14^b, on rack 49, when said bars are moved 10
toward the right, at which time, the succeeding 15
strap 14'', deflects ejectors into mortises 25'', (see Fig. 12,) as said ejectors pass said 20
strap, back to the position seen in Fig. 3. Push bar 26 in its movement toward the left 25
pushes the edge 50' of strap stop 50 and rotates 30
said stop from the position seen in Fig. 3 to the position seen in Fig. 5. The ends 35
of said strap stop are rotatably mounted in bearing brackets 51, secured to and carried 40
by table brackets 16, see Fig. 1. The return 45
rotation of said strap stop, is caused by the gravity thereof, after push bar 26 has moved 50
to the right from beneath said stop.

Referring to Figs. 13 and 6, strap stop 50 5
has mortises 50'' formed therein, to permit 10
passage therethrough of ejector bars 25. The face of said stop, which stops straps 14'', and the inner edge of feed plate 27 15
have clearance notches 50^a and 27^a, respectively 20
formed therein, to permit free passage 25
of the edges of such dies 40 as project past 30
the edges of straps 14'', seen in Fig. 13.

Referring to Fig. 1, on drive shaft 33 is 35
secured the bevel gear 53, engaging bevel 40
gear 54, formed with notched hub 54', loosely 45
mounted on splined shaft 55, rotatably 50
mounted in bearing brackets 56' and secured 55
on yoke 3'. The notch of said hub 60
is disengageably engaged by projection 58', 60
formed on collar 58, slidably splined on shaft 65
55, and provided with annular channel 58'', 70
engaged by fork 59' of lever 59, pivotally 75
secured to yoke 3'. The free end of said 80
lever is laterally elastic and is adapted to 85
be raised from the position seen and sprung 90
into notch 56'' in bracket 56; thereby 95
providing disengageable engaging means, whereby 100
drive shaft 33 is disengaged from its engagement 105
with the hereinafter described 110
skiver. On the rear end of shaft 55 is secured 115
the gear 60, engaging gear 61, secured 120
on the rear end of skiver shaft 62, rotatably 125
mounted in brackets 63, secured on yoke 3'. 130

Referring to Fig. 9, on shaft 62 is secured 50
the skiver body 64 carrying skiver blade 65, 55
secured thereon by screw 65'. Spring actuated 60
keeper 66, (adapted to keep that part 65
of strap 14'' in front of said skiver blade, 70
firmly pressed against skiver block 67,) is 75
secured to said skiver body by screws 66'. The inner end of skiver block 67 is pivotally 80
secured at 67' to skiver bracket 68, provided 85
with slots 68', through which pass screws 69, screwed into yoke 3', for adjustably 90
securing said bracket to said yoke. The outer end of said skiver block is provided 95
with adjusting screw 70, the lower end of which is pivotally secured at 70' to 100
said block, and the upper screw threaded 105
portion is adjustably secured in a loose aper-

ture through the end of arm 68'' of bracket 110
68, by lock nut 71 and thumb nut 72; thereby 115
providing adjusting means, whereby said 120
skiver block is thoroughly adjustable to said 125
skiver blade.

The described skiver is so timed with the 130
previously described movements of feed 135
plate 27 and die 40, that during the de- 140
scribed revolution of shaft 33, the cutting 145
edge of blade 65 travels in continuous rota- 150
tion, from point A to B, B to C, C to D, 155
and D back to point A, in consecutive order 160
during the described fractions of one revolu- 165
tion of shaft 33; from which it will be seen 170
and understood that said cutting edge passes 175
from point B to point C, while a strap is 180
being moved as described to the position 185
seen at 14'', unobstructed by the described 190
skiver; which is disengaged from shaft 33, 195
and stands still in this position, while straps 200
14'' are punched or die cut without skiving.

Having fully described my invention, what I claim as new and desire to secure by Letters Patent is;—

1. In a strap working machine, having a 90
table and a strap box adapted to removably 95
hold a pile of straps on said table; a plu- 100
rality of carrier bars, slidably mounted in 105
said table; a plurality of ejector bars, mount- 110
ed, one on each of said carrier bars, a feed 115
plate, adapted to feed said straps, one at a 120
time in succession from said strap box, ad- 125
justable securing means for said feed plate, 130
whereby said feed plate is adjustably secured 135
on said ejector bars, said securing means 140
also acting as securing means whereby said 145
ejector bars are secured on said carrier bars, 150
and reciprocative driving means, whereby 155
said feed plate is reciprocated beneath said 160
strap box.

2. In a strap working machine, the combi- 165
nation with die cutting means, provided 170
with cutting dies, adapted to die cut a strap, 175
of a rotatable skiver, having a skiver body, 180
provided with a skiver blade secured there- 185
on, adapted to skive an end portion of said 190
strap; rotating means, rotating said skiver, 195
and intermittent moving means, whereby 200
said cutting dies are moved, for die cutting 205
said strap, and held in said strap, and act as 210
holding means for holding said strap, while 215
said skiver is doing said skiving.

3. In a strap working machine, a skiver, 220
comprising a skiver body, secured on a ro- 225
tatably mounted shaft, said body being pro- 230
vided with a skiver blade, secured thereon, 235
adapted to skive an end portion of a strap; 240
a skiver block; supporting means, whereby 245
said block is supported adjacent to said 250
blade; adjusting means, for said block, 255
whereby the space between said block and 260
said skiver blade is adjusted; a spring actuated 265
keeper, secured on said body, said 270
keeper being adapted to keep said strap 275
firmly pressed against said skiver block, in 280

advance of said skiver blade, and rotating means, whereby said skiver is rotated.

4. In a strap working machine, having a frame for supporting the parts thereof and provided with a table adapted to support a pile of straps thereon; a strap box, adapted to removably hold said pile of straps on said table, said strap box being provided with securing means for slidably securing the same to said table; a strap box extension, slidably secured to said strap box, said extension being provided with a strap gage on the extended end thereof, and securing means, whereby said extension is secured to said strap box at various extensions therefrom.

5. In a strap working machine, a rotatably supported strap stop; rotating means, adapted to contact and rotate said strap stop into position to abut an edge of said strap and stop the same in said machine; said strap

stop being adapted to be rotated by gravity thereof, to a position below the level of said strap upon removal of said strap stop rotating means from contact with said strap stop, 25 and driving means, whereby said stop rotating means is reciprocatively driven into and from contact with said strap stop.

6. In a strap working machine, a plurality of ejector bars, each of which is provided 30 with a mortise formed therein, a spring ejector, secured on said ejector bar, said ejector being compressible into said mortise, and supporting, guiding and reciprocative driving means, whereby said ejector bars are supported, guided and reciprocatively driven. 35

In testimony whereof I affix my signature in the presence of two witnesses.

JAMES THORNTON.
